(57) **CLAIM**

The ornamental design for a container divider tab, as shown and described.

DESCRIPTION

FIG. 1 is a perspective view of a container divider tab showing the new design;

FIG. 2 is an enlarged view of the portion labeled “2” in FIG. 1;

FIG. 3 is an enlarged view of the portion labeled “3” in FIG. 1;

FIG. 4 is a front view thereof;

FIG. 5 is a rear view thereof;

FIG. 6 is a top view thereof;

FIG. 7 is a bottom view thereof;

FIG. 8 is one side view thereof;

FIG. 9 is an opposite side view thereof; and,

FIG. 10 is an alternative perspective view thereof.

The broken lines in the drawings depict portions of the container divider tab that form no part of the claimed design. The dash dot dash lines showing the enlargements in FIGS. 1, 2, and 3 form no part of the claimed design.

1 Claim, 7 Drawing Sheets(56)
